US0D1105135S

(12) **United States Design Patent** (10) Patent No.: **US D1,105,135 S**
 Adawi et al. (45) Date of Patent: ** Dec. 9, 2025

(54) **DISPLAY SCREEN OR PORTION THEREOF WITH ICON**

(71) Applicant: **Biosense Webster (Israel) Ltd.**, Yokneam (IL)

(72) Inventors: **Eid Adawi**, Tur'an (IL); **Avigdor Rosenberg**, Kiryat Tivon (IL)

(73) Assignee: **Biosense Webster (Israel) Ltd.**, Yokneam (IL)

(**) Term: **15 Years**

(21) Appl. No.: **29/987,540**

(22) Filed: **Jan. 24, 2025**

Related U.S. Application Data

(62) Division of application No. 29/861,391, filed on Nov. 29, 2022, now Pat. No. Des. 1,067,244, which is a division of application No. 29/727,707, filed on Mar. 12, 2020, now Pat. No. Des. 971,227.
